Primary Examiner — Katrina N Gonzalez(74) Attorney, Agent, or Firm — Jose Cherson Weissbrot(57) CLAIM

The ornamental design for a pet bowl, as shown and described.

DESCRIPTION

FIG. 1 is a perspective view of a pet bowl showing our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof;

FIG. 8 is another perspective view thereof, but shown in an elevated position of use;

FIG. 9 is a bottom perspective view, shown with the legs folded in for clarity of illustration; and,

FIG. 10 is another perspective view, but shown folded in half for clarity of illustration.

1 Claim, 10 Drawing Sheets(56)
